Primary Examiner — Brett Miller*Assistant Examiner* — Rani J Abdallah(74) *Attorney, Agent, or Firm* — Merchant & Gould P.C.(57) **CLAIM**

The ornamental design for a bottle for cosmetics, as shown and described.

DESCRIPTION

FIG. 1 is a top perspective view of a bottle for cosmetics; FIG. 2 is a front elevational view thereof; FIG. 3 is a right side elevational view thereof, a left side elevational view not being shown as it is a mirror image of the right side elevational view; and, FIG. 4 is a top view thereof. The bottom is devoid of ornamentation.

1 Claim, 4 Drawing Sheets(56)
